UNITED STATES PATENT OFFICE.

CHRISTIAN FREDERICK, OF WILMINGTON, DELAWARE, AND JOHN C. EGLEY,
OF PHILADELPHIA, PENNSYLVANIA; SAID EGLEY ASSIGNOR TO THOMAS
A. PEARCE, OF PHILADELPHIA, PENNSYLVANIA.

CIRCULAR-KNITTING MACHINE.

SPECIFICATION forming part of Letters Patent No. 408,007, dated July 30, 1889.

Application filed April 13, 1889. Serial No. 307,084. (No model.)

To all whom it may concern:

Be it known that we, CHRISTIAN FREDERICK, of Wilmington, in the county of New Castle and State of Delaware, and JOHN C. EGLEY, of Philadelphia, in the county of Philadelphia and State of Pennsylvania, have invented certain Improvements in Circular-Knitting Machines, of which the following is a specification.

10 This invention has reference to cylinder knitting-machines in which a series of vertical needles are reciprocated by cams on the inside of a rotary encircling-ring, commonly known as the "cam-ring." In the use of these
15 machines for knitting heels and toes, or other work requiring the fabric to be narrowed or widened, it is the common practice to lift certain of the needles until their heels are out of the reach of the operating-cams. It is
20 found, however, that from various causes the heels of the needles are liable to descend or ascend accidentally to such position that they will strike squarely against the ends or points of the operating-cams, instead of riding there-
25 under or thereover, as they should do. In machines for fine work, having the needles set closely together, the contact of the needles with the point of the cam causes the breakage of the cylinder, the thin metal walls be-
30 tween the needle-grooves being fractured.

Our invention relates to a guard-cam or safety-cam designed to act upon the heels of such needles as are in danger of striking the point of the cam to force the same either up-
35 ward or downward that they may pass the cam in safety.

We are aware that cams have heretofore been devised for this purpose; but our invention relates to a peculiar construction and
40 arrangement, hereinafter recited in detail, whereby the cams are given a new mode of action and relieved from the dangers and objections attending the cams heretofore in use.

In the accompanying drawings, Figure 1 is
45 a vertical central cross-section of the cam ring or cylinder having our improvement applied thereto. Fig. 2 is a horizontal section of the same on the line $x x$. Fig. 3 is a vertical section on the line $y y$ of Figs. 1 and 2.

Fig. 4 is a perspective view of one of the 50 safety-cams as seen from above. Fig. 5 is a similar view of the same as seen from its under side. Fig. 6 is a cross-section on the line $z z$ of Figs. 1, 2, 4, and 5. Figs. 7 and 8 are plan views illustrating the action of the needles on one of the safety-cams. Figs. 9, 10, and 11 are face views showing various positions of the needle in relation to the cam.

55 Referring to the drawings, A represents a rotary cam-ring provided with the fixed cams $a a' a'' a'''$, constructed and arranged in the usual manner to effect the elevation and depression of the operated needles at each revolution of the ring.

Our improvement is intended to prevent 65 the needle-heels from striking against the points or ends of the upper cam a''' , and for this purpose we employ at opposite ends of said cam our two safety-cams B and B'. These cams, which operate independently of each 70 other and during the rotation of the cam-ring in opposite directions, are precisely alike, except that one is right and the other left handed. A description of the construction and operation of one cam will therefore be 75 a sufficient explanation of the other. Selecting, therefore, the cam B for illustration, it will be seen to consist of a plate extending horizontally through a slot in the cylinder from the outside, where it is mounted on 80 a supporting-pivot b , supported in legs on the cam-ring. At its outer end, near the pivot, the cam is shouldered, and is acted upon by one end of a spring b' , fixed to the cylinder and urging the inner end of the cam through 85 and beyond the inner face of the ring. The inner projecting end of the cam is made of the peculiar form shown particularly in Figs. 4 and 5. It presents on the upper side a flat surface b^3 , which extends from the lower front 90 edge upward and backward toward the cam a''' to a level above the point of the cam, so that the needle-heels riding over the surface b^3 will be lifted thereby above the point of cam a''' . At the forward edge the point of the cam 95 is cut away in the peculiar manner shown at b^4 . This cut extends somewhat into the upper surface b^3 ; but a square point or shoul-

der b^5 is left at the forward edge, as shown. On the under face the point of the cam is cut away from the opening b^4 backward, as shown at b^6 , to present a rounded surface having a 5 downward and backward inclination. Viewed from the inside of the cylinder the cam presents the appearance shown in Fig. 9.

In vertical cross-section the upper face b^3 and the under face b^6 are horizontal, as shown 10 in Fig. 6. This horizontal position of these faces is an important feature of our construction and is to be particularly noted.

The action of the device is as follows: As 15 the point of the cam a^3 is advanced toward a needle-heel in its path, it is preceded by the cam B. If the heel is in such position that its side face strikes squarely against the front shoulder b^5 of the cam, as shown in Fig. 7, the cam will be tipped backward or outward through the cam-ring, as shown in Fig. 20 8, after which the heel will ride either upward over the face b^3 or downward under the face b^6 , so that it will pass in the one case over and in the other case under the cam a^3 .

25 In practice we have found a cam constructed and mounted as described will invariably throw the needle-heel upward or downward and that it is impossible for needles to lodge firmly against said cam or to pass the same 30 in any position in which they could abut against the end of the cam a^3 .

Owing to the fact that the faces b^3 and b^6 are 35 horizontal in cross-section, the needle-heels have but slight tendency to urge the cam outward. Consequently we are enabled to employ a feeble spring to hold the cam in position, and thus to overcome the dangers which would attend the use of a cam requiring the support of a strong spring and requiring the needles 40 to apply a heavy pressure before the cam will yield. This has been a serious difficulty with safety-cams as heretofore constructed. In the previous cams the needle-depressing surfaces were inclined in cross-section, so that 45 the resistance of the cam tended to force the cam outward. It was consequently necessary to employ springs of such great strength that their resistance frequently caused the needles to fracture the guides in the cylinder. It will 50 be observed that the upper inclined face b^3 is continued downward below the level of and beyond the upper end of the under surface b^6 . It follows, therefore, that any needle which strikes against the end or shoulder b^5 will, 55 after swinging the cam outward, be certain to pass through the notch b^4 and under the cam.

The outward motion of the cam acts to carry the upper surface b^3 out of the way and to present the under surface b^6 in a new position in which it is exposed to the needle-heel, 60 so that the latter may pass thereunder. In other words, when the cam is in its normal position a heel at a level with its end will not ride thereover and cannot ride thereunder, because the shoulder or end b^5 prevents the 65 heel from reaching the under surface. When the cam turns back, the shoulder passes out of the way and exposes the surface b^6 at a higher level, so that the heel is certain to pass thereunder. 70

Having thus described our invention, what we claim is—

1. In combination with the ring provided with the usual needle-operating cams, the spring and the spring - actuated guard-cam 75 pivoted to swing outward and provided at the inner end with surfaces b^3 b^6 , inclined one upward and the other downward in the direction of rotation.

2. In combination with the ring having the 80 usual needle-operating cams, the outwardly-movable spring-pressed guard-cam having at its inner end an upwardly and a downwardly inclined surface, one having its forward end carried past the level of the other, whereby 85 the outward motion of the cam is caused to expose to the needle-heels the surface which was previously guarded by the other surface.

3. The ring having the usual needle-operating cams, in combination with the spring 90 and the pivoted spring-pressed guard-cam having the surfaces b^3 b^6 , shoulder b^5 , and notch b^4 .

4. In combination with the ring and the usual needle - operating cams, the pivoted 95 spring-pressed guard-cam having, first, an upper inclined face normally in the path of those needle-heels which would abut against the point of the operating-cam; second, the shoulder against which said heels act to swing the cam outward, and, third, the under inclined surface which is exposed to the heels by the outward motion.

In testimony whereof we hereunto set our hands, this 30th day of March, 1889, in the 105 presence of two attesting witnesses.

CHRISTIAN FREDERICK.
JOHN C. EGLEY.
